UNITED STATES PATENT OFFICE.

HORACE H. TAYLOR, OF SAN FRANCISCO, CALIFORNIA, ASSIGNOR OF ONE-HALF TO
JOHN D. BLUXOME, OF SAN FRANCISCO, CALIFORNIA.

PUMP.

Application filed February 24, 1925. Serial No. 11,152.

To all whom it may concern:

Be it known that I, HORACE H. TAYLOR, a citizen of the United States, residing at San Francisco, in the county of San Francisco and State of California, have invented new and useful Improvements in Pumps, of which the following is a specification.

The present invention relates to an improved pump having oscillating pistons and which is constructed in a simple and compact manner, the said pump being also inexpensive as to construction and operation.

One of the objects of the invention is to provide a pump of the character described which may be readily assembled and disassembled and in which the wear on the working parts is minimized.

The invention takes into consideration the particular construction and relative arrangement of the pistons and associated parts, due to which, the pump is made exceptionally strong and durable and has a comparatively great pumping capacity in proportion to the amount of power required to operate it.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

Referring to the drawings;

Fig. 1 represents a vertical sectional view of a pump constructed in accordance with the present invention.

Fig. 2 represents a top plan view of the pump of the invention, parts being broken away and shown in section for the sake of clearness of illustration.

The embodiment of the pump shown in the accompanying drawings comprises a semi-cylindrical pump chamber made up of a semi-cylindrical body 1 provided with removable end walls or heads 2 and 3 bolted thereto. The pump chamber body 1 is bolted onto the upper side of an intake chamber 4, the upper wall 5 of which chamber constitutes the lower wall of the pump chamber. The end walls of the intake chamber are

formed integral therewith and the removable walls extend over and lie against the outer sides of the end walls of the intake chamber. Flanges 6 and 7 are provided on the intake chamber and are engaged by lower extremities of the walls 2 and 3, being bolted thereto. The intake chamber is provided with an intake opening 8 at its lower side, around which opening there is provided an attaching flange 9 to provide for connecting the intake chamber with a suitable conduit or pipe, not shown.

The intake chamber is provided with suitable legs 10 which adapt the chamber as a base or support for the pump chamber. In the upper side of the pump chamber there is provided an outlet or discharge opening 11 around which is provided an attaching flange 12 corresponding to the flange 9.

The pump chamber is divided into two compartments designated A and B, by an upright partition 13, each of which compartments constitutes a pump chamber. Extending through the pump chambers A and B are shafts 14 and 14' having suitable bearings 16 and 17 in the end walls 2 and partitions 13. Surrounding and keyed to these shafts are sleeves 18 and 18'. These sleeves have semi-circular bearings 19 provided on the wall 5. The sleeves are provided with longitudinal ribs or projections 20 and 20', the formation of which define shoulders 21. These projections 20 and 20' are adapted to engage in grooves 22 extending longitudinally in the web portions 23 which join the two pistons or impellers 24 and 25 of the pairs designated C and D and located in the compartments A and B respectively. By means of screw bolts 26 these web portions are fastened to the sleeves 18, the said bolts being turned onto the ribs or projections, thereby securely but removably fastening the pairs of pistons to the shafts. The bearing of the under sides of the webs against the shoulders 21 insures a rigid and secure joining of the pairs of pistons with the sleeves.

The two pistons of each pair extend substantially at right angles to one another and each is provided with an opening 27 in which a bushing 28 is secured, there being a spider 29 extending across said bushing. Secured onto the center of the spider is a stem 30 on which a valve 31 is loosely mounted. This valve is adapted to seat against the flanged end of the bushing 28 to close the opening

through the piston. A helical expansion spring 32 is mounted on the stem and one end bears upon the the valve whereas the other end engages an abutment 33 adjacent the outer end of the stem. This spring tends to hold the valve closed. The edges of the pistons are provided with suitable packing 35 so that the pistons will have the proper working fit in 10 the pump cylinders.

The pair D of the pistons located in the chamber B is arranged in offset relation to the pair C in the chamber A. This arrangement provides for the commencement of 15 the pumping or impelling action of one of the pistons of the pair C before the completion of the pumping stroke of one of the pistons of the pair D. This provides for a continuous flow of liquid from the pump.

20 In the wall 5 in communication with each of the pumping compartments A and B, is a pair of intake openings 36 and 37 in which flanged bushings 38 are secured. These openings are provided with valves 39 and 25 40 which seat upon the upper sides of the bushings. Stems 41 depend from the valves through spiders 42 carried by the bushings and have abutment members 43 on their lower ends against which the lower ends of 30 expansion springs 44 engage. These springs surround the stems and at their upper ends abut the spiders 42. These valves are alternately opened and closed by the action of the impellers or pistons.

35 Mounted on the ends of the shafts 14 and 14' are crank arms 45 and 46, to the outer ends of which pitmen 47 and 48 are connected. These pitmen are connected with 40 crank arms 49 and 50 fixed to a shaft 51 journaled in bearings 52 carried by the pump. A gear 53 is fixed to the shaft 51 and meshes with a similar gear 54 fixed to a shaft 55 journaled in bearings 56 on the pump casing. Any suitable means, not 45 shown, may be employed to drive the shaft 55. The crank arms 48 and 50 are set at different angles as are the crank arms 45 and 46. This provides for the timed operation 50 of the pairs of pistons designated C and D.

55 In the operation of the pump, when the pistons 24 and 25 of the pair D are in the position shown in dotted lines in Fig. 1, the piston 24 is in substantially the middle of its pumping stroke with the valve thereon open. These pistons are moved in the direction shown by the dotted arrow. At this time the valve on the piston 25 of the pair D is closed by the pressure of the liquid.

60 The force of the piston 24 against water contained in the part of the pump chamber B, between the piston 24 and the wall 5, causes the liquid to pass through the valve opening in the piston 24 into the space between the pistons and out through the dis-

charge opening 11. During the movement of the pistons 24 and 25 (chamber B), the piston 25 which contains the valve 39 sets up a suction and causes water contained in the intake chamber 8 to pass into the pump chamber B behind the piston 25. When the piston 24 moves past its dotted position shown in Fig. 2, the pistons 24 and 25, of the pair C shown in full lines Fig. 2, begin to move in the direction shown by the full line arrow in Fig. 2. Thus, the piston 25 commences to pump or force the water contained between it and the valve 39 of the chamber C, through the valve opening in the piston 25 and into the space between the pistons 25 and 24 out through the opening 11. During this movement of the piston, the piston 24 sets up a suction action against and opens the valve 40 in the chamber A and induces a charge of water through said open valve into said chamber A behind the piston 24. This charge is subsequently forced through the valve on the piston 24 when said piston moves in the opposite direction on its working stroke. The pistons, 90 due to the drive arrangement, are oscillated as described and due to the fact that one piston of each pair ceases its pumping operation, a continuous discharge of liquid from the pump is provided for. The arrangement of the pistons is such that one piston of each pair is at all times drawing in a charge of liquid to be pumped during the pumping of a previously drawn in charge by the other piston.

95 By having pairs of pistons arranged as described, the pump operates smoothly and continuously and has a greater capacity.

I claim:

1. An oscillating pump comprising a 105 semi-cylindrical pump chamber having an outlet opening on its upper side, an intake chamber around which the pump chamber is mounted, the upper wall of which intake chamber comprises a lower wall of the pump 110 chamber, said upper wall having intake openings therein, valves controlling said openings, shafts extending into said pump chamber, a partition dividing said pump chamber into separate pumping chambers, 115 each of which communicates with said discharge opening and with openings in said upper wall, a pair of pistons fixed to each shaft and located in each of the separate chambers, the pistons of said pairs being 120 extended substantially at right angles to one another, openings extending through said pistons and valves controlling said openings.

2. An oscillating pump comprising a 125 pump chamber having an outlet opening on its upper side, an intake chamber above which the pump chamber is mounted, the upper wall of which intake chamber comprises the lower wall of the pump chamber.

ber, said upper wall having intake openings therein, valves controlling said openings, a partition dividing the pump chamber into separate compartments, shafts extending into said compartments, a pair of pistons fixed to each shaft located in each of the separate compartments, which pistons extend at right angles to one another, openings extending through said pistons, valves controlling said pistons, the pistons of one pair being angularly related to the pistons of the other pair, said shafts having a bearing engagement with one another at their inner ends and subject to oscillation in opposite directions and means for so oscillating said shafts.

3. An oscillating pump including a pump chamber, an intake chamber above which said pump chamber is mounted, the upper wall of which intake chamber comprises the lower wall of the pump chamber and is provided with openings, valves controlling said openings, a shaft extending into said pump chamber, a bearing for the shaft on the upper side of said wall, a pair of pistons joined and extending at right angles to one another, there being a web portion by which said pistons are joined,

said web portion having a groove therein, a key on the shaft defining shoulders on opposite sides thereof, which key engages in the groove and a fastening element extending through said web and into said shaft, said pistons having openings therein and valves controlling said openings.

4. An oscillating pump comprising a pump chamber having an outlet opening in its upper side, an intake chamber above which said pump chamber is mounted, the upper wall of said intake chamber comprising the lower wall of the pump chamber, a partition dividing said pump chamber into separate compartments, said upper wall having openings therein, valves controlling said openings, shafts extending into said compartments, one of said shafts being extended through said partition and having a bearing engagement with the other shaft, said shafts being subject to relative oscillation movement, a pair of pistons fixed to each shaft and located within each compartment, pistons having openings therein, valves controlling said openings and means for oscillating said shafts.

HORACE H. TAYLOR.
